(57) **CLAIM**

The ornamental design for a laser projector lamp, as shown and described.

DESCRIPTION

FIG. 1 is a front, left and top perspective view of a laser projector lamp showing my new design;
FIG. 2 is a right, rear and bottom perspective view thereof;
FIG. 3 is a front view thereof;
FIG. 4 is a rear view thereof;
FIG. 5 is a left side view thereof;
FIG. 6 is a right side view thereof;
FIG. 7 is a top plan view thereof; and,
FIG. 8 is a bottom plan view thereof.
The broken lines in the figures illustrate portions of the laser projector lamp that form no part of the claimed design.
